UNITED STATES PATENT OFFICE.

GUSTAF S. BECKMAN, OF CRANSTON, RHODE ISLAND, ASSIGNOR TO UNIVERSAL WINDING COMPANY, OF BOSTON, MASSACHUSETTS, A CORPORATION OF MASSACHUSETTS.

TENSION DEVICE.

Application filed October 11, 1926. Serial No. 140,977.

This invention relates to improvements in tension-devices for use with winding machines and other textile apparatus.

One object of the invention is to provide a self-threading tension-device in which the strand of yarn, thread or other filament is automatically threaded into place in the device under the draft of its feed to the winding or other machine.

Another object of the invention is to provide a tension-device in which the mechanism is so constituted and arranged as to prevent the collection of lint, fluff, motes and other impurities thrown off from the yarn or thread and liable to clog its operation.

Another object of the invention is to provide a tension-device of simple construction having a minimum number of parts and one which is more durable in use and more efficient for the purpose intended.

Another object of the invention is to provide a tension-device in which the parts may be constructed of sheet-metal to render them light in weight and economical to manufacture.

Another object of the invention is to provide a combined tension-device and slug-catcher or yarn-cleaner for clearing the strand of slugs, bunches, motes or the like adhering to the yarn.

Further objects of the improvement are set forth in the following specification which describes a preferred embodiment of the invention as illustrated in the accompanying drawings. In the drawings:

Fig. 1 is a plan view of the improved tension-device shown as attached to its supporting bracket;

Fig. 2 is a side elevation of the same;

Fig. 3 is an end elevation looking in the direction indicated by the arrow in Fig. 1;

Fig. 4 is a sectional elevation of the device taken on line 4—4 of Fig. 1; and

Fig. 5 is a sectional detailed view taken on line 5—5 of Fig. 4.

The present improved tension-device is adapted for use particularly with windings or like machines in which the strand of yarn, thread or other attenuated material is drawn off from a cop, bobbin or other source of supply and fed to the machine to be taken up by the winding or other process. The tension-device may be mounted on any suitable support and as herein illustrated is attached to an arm or bracket 2 which is adapted to be

fastened to the frame of the winding machine or other apparatus. As before indicated, the present improved tension-device is constructed principally of sheet-metal stampings and comprises in general a flat base-plate 3 having a V-shaped contour in plan view with two tapering prongs or horns 4 and 5 diverging from a narrow slit or threadway 6 at its center. The base-plate 3 is folded or bent downwardly at its rearward side to provide a vertical flange or lip 7 which is adapted to be received within a slot 8 milled through an upstanding lug or post 9 on the bracket 2. A screw 10, threaded through a lateral hole in the lug or post 9 with its head countersunk into one side thereof, passes through a hole in the flange 7 to secure the base-plate 3 in position on the bracket. A portion of the flange 7 is sheared away at 11 and bent around in an arm 12 which is provided with a slot 13 at its end forming an elbow-like hook 14, see Fig. 5. The arm 12 serves as the means of support for a tension-lever 15 to be later described.

Overlying the top of the prong 4 on the base-plate 3 is a plate 24 shaped to the general contour thereof and extending rearwardly beyond the flange 7 in a rectangular portion 25. The forward edge 26 of the top plate 24 extends diagonally back from the slit or threadway 6 to adapt it to function as a guiding face for directing the strand into the threadway 6 and through the tension-device in the manner as hereinafter more particularly explained. The forward part of this diagonal portion of the plate 24 is curved or convexed upwardly at 27 to provide an entrance for the strand into the threadway 6, it being noted that the top plate 24 is secured to the top of the base-plate 3 by means of rivets 28 and 29 shown in Figs. 1 and 3.

The rearward rectangular portion 25 of the top plate 24 is formed with a lateral slit or opening 30 and a portion of the stock of the plate is bent downwardly along its inner edge to form a vertical flange 31. Abutting the side of the flange 31 is a slug-catcher member 33 comprising an arm 34 bent around at its end to form a right-angled blade 35. The arm 34 is pivotally mounted at its end on a pin 36 projecting from the side of the flange 31. A screw 37 inserted through a washer 38 projects through an enlarged hole 39 at the outer end of the arm 34 and is screwed into the side of the flange 31. This means for

mounting the slug-catcher member 33 provides for adjustment of its blade 35 with respect to the under side of the top-plate 24 to set the blade with an opening between its upper working edge and the bottom of the plate. By loosening the screw 37 the blade may be set at different distances away from the plate 24 to provide a slit or opening of the proper width to accommodate the strand 10 drawing therethrough in accordance with the size or thickness of the yarn. It will be noted from Figs. 2 and 3 of the drawings that the outer end of the slug-catcher blade 35 is beveled off or inclined at 40 to adapt the 15 strand to draw thereacross to lead it into the slit or opening 41 above the upper edge of the blade. It is also to be observed that the base-plate 3 is formed with a rearwardly extending strip or arm 42, see Fig. 1, which reaches 20 back nearly to the blade 35 and has a finger 43 at its end projecting inwardly in parallel relation with the blade. The arm 42 is offset or depressed below the lower face of the top-plate 24, see Fig. 2, to provide a clearance 25 for the strand as it draws beneath the edge 26. The purpose of this arm 42 is to guide the strand into the slug-catcher and to prevent it from looping or catching around any of the parts arranged beneath the base-plate 3.

The tension-lever 15, previously referred to, consists of a sheet-metal stamping constructed with an inclined arm 16, an offset horizontal arm 17 and a vertical prong or 35 pin 18. The main arm 16 of the lever 15 is provided with a slot or opening 19 of substantially triangular or wedge shape to adapt it to be hooked into the slot 13 to rest on the hook 14 of the arm 12 as shown most clearly in Figs. 40 4 and 5. The lever 15 is thus pivotally mounted without recourse to the use of pins, screws or other extraneous parts and is adapted to be applied to or removed from operative position without the use of tools. The upper 45 portion of the arm 16 of the lever 15 carries a vertical stud or pin 20 projecting through a hole 32 in the top-plate 24 and on which is mounted a tension-disk 45. The stud 20 has an enlarged butt-end 21 which is slotted at 50 22 to straddle the sides of the lever 15, being pivoted thereto by means of a cross-pin 23.

The tension-disk 45 is constructed of sheet-metal stamped or punched to generally concavo-convex shape in cross-section as illustrated in Fig. 4. The upper convex surface of the disk is adapted to bear against the under side of the top-plate 24 with its rim flaring away therefrom to provide a free entrance for the strand to thread it into place 55 therebetween. Beneath the disk 45 is a relatively light helical spring 46 surrounding the stud or pin 20 and tending to maintain the disk bearing against the top-plate 24 in the manner and for the purpose as hereinafter 60 more fully explained. The upright prong or

pin 18 on the arm 17 of the lever 15 is adapted to receive one or a plurality of disk-shaped tension-weights 47 which tend to rock the lever to apply pressure through the spring 46 to maintain the tension-disk bearing 70 against the under side of the top-plate 24, a greater or less number of weights being employed in accordance with the degree of tension to be applied to the strand drawing through the tension-device. 75

Having now described a preferred form of construction of the invention its method of operation will next be explained. In threading the tension-device the strand *y* of yarn, thread or other filament is drawn up from its source of supply, arranged below, laid in the crotch formed by the flaring edges of the horns 4 and 5 and then drawn rearwardly across the top of the plate 3 and along the diagonal edge 26 of the top-plate 24. The end of the strand is carried through the thread-guide of the winding machine to which the yarn is to deliver and fastened to the winding spindle or other take-up means. As the winding spindle starts to rotate it will draw the strand through the crotch between the prongs 4 and 5 to cause it to enter the treadway 6 while drawing in under the edge 26 of the top-plate 24. The strand *y* is thus directed in under the top-plate 24 so that it 80 will be drawn into place between the bottom face of said plate and the convex surface of the tension-disk 45 and also into position in the opening 41 above the slug-catcher blade 35. The yarn is thus automatically threaded into place as indicated by dot-and-dash lines in Fig. 1 to draw from the treadway 6 through the tension-device and slug-catcher as it feeds to the winding or other machine. 85 As the strand *y* feeds through the tension-device in this manner the pressure of the weights 47 will cause the tension-disk 45 to bear against it on the under side of the top-plate 24 with a yielding pressure as exerted by the spring 46; the purpose of the spring being to provide a buffer or shock-absorber which allows the disk to yield or move away from the plate 24 when knots or other enlargements on the strand pass through the device so as not to disturb the inertia of the lever 15 and its weights 47. In this way a 90 more constant and uniform tension is applied to the yarn without fluctuations due to sudden release of the pressure when abnormalities on the yarn are encountered, such as 95 knots, bunches, slugs or the like. 100

It will be observed from the above that my invention provides a particularly simple and compact tension-device in which substantially all of the parts are constructed from sheet-metal punchings or stampings to provide lightness of weight and economy in the cost of manufacture. The tension-device is automatically self-threading to relieve the operator of care or attention and further to 105 110 115 120 125 130

insure that the strand of yarn, thread or other filament shall invariably be correctly inserted into position for proper functioning of the devices. The improved tension-device also embodies a slug-catcher or yarn-cleaner of simple construction and in its entirety comprises a minimum number of parts.

The improved device is practically proof against clogging with dirt or lint, it being particularly noted that the tension-disk is supported beneath the plate on which it bears in such manner as to eliminate any shelf or ledge liable to gather lint, motes and other impurities thrown off from the yarn. That is to say, all lint, fluff, dirt, specks or the like issuing from the rim of the tension-disk as the yarn feeds therethrough will be thrown off and dropped down below without gathering on any of the parts, the under side of the disk being unsupported except at its axis. If the device requires cleaning after long periods of use access to the tension-disk is made convenient by simply unhooking the tension-lever 15 and withdrawing the tension-pin or stud 20 from the hole in the top-plate 24. Likewise, the replacing of the tension-disk and its pressure lever in operative position is equally convenient, no screwdriver, wrench or other tools being required.

While I have herein illustrated a preferred embodiment of the device it is to be understood that various modifications may be made in the structure and arrangement of its parts without departing from the spirit or scope of the invention.

Therefore, without limiting myself in this respect, I claim:

1. A tension-device comprising a stationary element across which the strand draws and provided with an opening, a pin projecting through the opening at substantially right-angles to the under face of said element, a support for said pin, a tension-disk mounted on said pin beneath said element, and means for pressing said disk against the element to apply resistance to the draft of the strand passing therebetween.

2. A tension-device comprising a stationary plate across the under side of which the strand draws and provided with an opening, a vertical pin projecting upwardly through the opening at substantially right-angles to said plate, a support for said pin, a tension disk on said pin, resilient means for holding the tension-disk against the under side of the plate, and means for applying pressure to the resilient means to cause the tension-disk to bear against the strand to apply resistance to its draft.

3. In a tension-device, the combination of a stationary member across the under side of which the strand draws, said member provided with an opening, a pivoted lever, a pin carried by said lever and slidable through the opening in the member, a tension-disk

mounted on said pin to adapt it to bear against the under side of the member, and a weight for rocking said lever to cause the disk to bear against the strand to apply resistance to its draft.

70

4. In a tension-device, the combination of a stationary plate provided with an opening, a lever pivoted below the plate, a pin carried by the lever and slidable through the opening in the plate, a tension-disk mounted on said pin in position to bear against the under side of the plate, and a weight on the lever tending to rock the latter to apply pressure to the disk to cause it to resist the draft of the strand drawing between the plate and the disk.

75

5. In a tension-device, the combination of a tension-member across which the yarn draws, said member provided with an opening, a lever pivoted beneath said member, a pin at one end of the lever arranged to slide through the opening in the tension-member, a tension-disk mounted on said pin, a spring on the pin arranged beneath the tension-disk, and means tending to rock the lever to apply pressure through the spring to cause the disk to bear against the strand to resist its draft to apply tension thereto.

85

6. In a tension-device, the combination of a stationary plate provided with an opening, a lever pivoted below the plate, a pin carried by said lever and slidable through the opening in the plate, a tension-disk mounted on said pin, a helical spring coiled around the pin and bearing on the under side of the tension-disk, and weights on the lever acting to rock the latter to apply pressure through the spring to cause the disk to bear against the strand to apply tension thereto.

90

7. In a tension-device, the combination of a stationary plate provided with an opening, a hook beneath said plate, a lever formed within opening to adapt it to be pivotally suspended on the hook, a pin carried by said lever and projecting through the opening in the plate, a tension-disk mounted on the pin to adapt it to bear against the under side of the plate, and means for rocking the lever to apply pressure to the disk to adapt it to bear against the strand.

105

8. In a tension-device, the combination of a base-plate provided with a threadway for the strand, a top-plate overlying the threadway in the base-plate and provided with an opening, a pin projecting through said opening, a tension-disk mounted on said pin to bear against the under side of the top-plate, and means acting against the disk to cause it to bear against the strand drawing between the disk and the top-plate to apply resistance to its draft.

110

9. In a tension-device, the combination of a base-plate having a threadway with prongs diverging outwardly therefrom, a top-plate overlying the threadway in the base-plate

130

and arched upwardly therefrom, a tension-disk arranged to bear against the under side of the top-plate, and means for applying pressure to the tension-disk to adapt it to bear against the strand drawing between the disk and the top-plate to cause resistance to its draft.

10. In a tension-device, the combination of a base-plate formed with a threadway for the strand and provided with a depending flange having an integral offset arm with a hook at its end, a top-plate overlying the base-plate and provided with an opening, a lever rockably suspended on the hook on the arm of the base-plate, a pin carried by said lever and arranged to project through the opening in the top-plate, a tension-disk mounted on the pin and adapted to bear against the under side of the top-plate, and means to rock 15 the lever to apply pressure to the tension-disk to cause it to bear against the strand passing between the disk and the top-plate to cause resistance to its draft.

11. In a tension-device, the combination of a base-plate provided with a threadway, a top-plate secured in overlying relation with respect to the base-plate and extending rearwardly therefrom with a depending flange at its side, a slug-catcher member adjustable 20 on the flange of the top-plate and provided with a blade adapted to be set in spaced relation with respect to the under side of the top-plate, a tension-disk adapted to bear against the under side of the top-plate, and means to 25 apply pressure to said disk to adapt it to resist the passage of the strand between the disk and the top-plate as it draws through the slug-catcher.

12. In a tension-device, the combination of 30 a slotted bracket, a base-plate formed with a threadway for the strand and provided with a depending flange adapted to be held in the slot of the bracket, a top-plate fastened to the top of the base-plate and having a portion

arched above the threadway, and tension-means adapted to bear against the strand as it draws through the threadway and across the under side of the top-plate. 45

13. In a tension-device, the combination of a tension-member across which the strand draws, a hook beneath said member, a sheet-metal lever suspended on said hook and provided with an upright prong, weights carried on said prong, a tension-disk adapted to bear against the under side of the tension-member, and resilient means arranged between the lever and the tension-disk to cause the lever to exert pressure on the disk to apply resistance to the draft of the yarn passing between the disk and the tension-member. 50 55 60

14. In a tension-device, the combination of a base-plate formed with a threadway and prongs diverging outwardly therefrom, a top-plate overlying the base-plate and arched above its threadway with one of its edges inclined rearwardly therefrom, and a tension-disk adapted to bear against the under side of the top-plate to apply resistance to the draft of the strand drawing through the threadway and beneath the top-plate. 65 70

15. In a tension-device, the combination of a base-plate provided with a threadway with prongs diverging outwardly therefrom, a top-plate overlying the base-plate with its forward portion arched above the threadway 75 therein, said top-plate formed with an inclined edge leading rearwardly from the threadway and raised above the base-plate, and tension-means cooperating with the rearward portion of the top-plate to apply resistance to the draft of the yarn, said top-plate arranged with its inclined edge adapted to direct the strand into the tension-device as it draws rearwardly from the threadway in the base-plate. 80 85

In testimony whereof I hereunto affix my signature.

GUSTAF S. BECKMAN.
